UNITED STATES PATENT OFFICE.

CLARENCE H. PICKERING AND JOHN CAMPBELL, OF SEATTLE, WASHINGTON, ASSIGNEES TO SWAN HEATING COMPANY, OF SEATTLE, WASHINGTON, A CORPORATION OF WASHINGTON.

SHEET-METAL RADIATOR.

Application filed December 31, 1925. Serial No. 78,546.

Our invention relates to radiators and is concerned chiefly with the construction and assembly of pressed metal radiators.

Radiators of thin pressed metal, copper for example, will require less time to heat up and will more readily give up their heat than the heavier cast metal radiators. This renders them especially desirable as portable radiators, where quick heating is an essential. Moreover, they may be made in pleasing designs and at less cost than cast radiators, and can be plated readily or painted to harmonize with their surroundings. The chief drawback to their general use has been the difficulty of so assembling these radiators that they can be readily disassembled for the replacement of a damaged or leaking unit, the construction heretofore used, so far as we are aware, making it necessary to permanently connect all units of such a radiator so that when a single leak developed it became necessary to discard the entire radiator. Further, the complete assembling of the entire radiator during the course of its manufacture at the factory heightened the initial cost of the radiator and shipping costs.

Important objects of our invention are, therefore, to provide a radiator which can be made of thin sheet metal, and of soft metal, as copper, if this be desirable; which can be assembled from the pressed plates without an expensive investment in machinery and, therefore, which can be pressed into shape at the factory, shipped knocked down, and assembled at the destination, or which can be assembled into single units which can be more conveniently shipped than a complete radiator, and from which radiators of as many units as are desired can be assembled without the necessity of special tools; and to provide a radiator of pressed metal which can be disassembled and repaired and again assembled, or in which a damaged or leaky unit can be replaced without the use of special tools.

A further object is the provision in a radiator, particularly one of this type, of a construction providing a cheap and convenient mounting for a heating element.

A further object is the general cheapening of the cost and the improving of the assembly of such radiators.

Our invention comprises the novel parts

and combinations thereof, as shown in the accompanying drawings, described in the specification and particularly defined in the claims terminating the same.

In the accompanying drawings, we have shown our invention in a form now preferred by us.

Figure 1 is a part vertical section and part side elevation of a complete radiator;

Figure 2 is a transverse vertical section through a unit of the radiator;

Figure 3 is a transverse section on line 3—3 of Figure 2.

A radiator made in units which are to be separable after assembly, must be clamped together in some way. Units of pressed sheet copper or like soft metal would not stand such clamping but would collapse or would leak at the joints. Thus our invention is concerned with the provision of means whereby such units of thin soft metal may be so clamped together that they are readily separated, and so that they will not collapse under sufficient pressure to hold their joints tight.

The units are shown as composed of two halves 1 and 10. These halves are, in general, alike but reversed, and the units are shown as providing a central aperture 11 defining two vertical columns 12; thus the units have inner and outer margins which must be secured, and this securing of the two halves is conveniently accomplished by a double crimp or like joint, indicated at 13, this being common in sheet metal working, and being capable of accomplishment by the use of tools usually readily available. Thus the nested halves of a great number of units may be shipped in a small space prior to assembly into the units, and conveniently assembled at their destination.

In assembling them, spacers 2 and 3, preferably in the form of apertured rings, are interposed between the two halves of a given unit. It will be understood that the halves of the units are apertured, the apertures being in alignment and affording communication between the several units. These apertures 14 and 15 are surrounded by the spacer rings 2 and 3, respectively, the rings lying just outside of the apertures, and when assembled in a radiator defining transverse tubular channels 22 and 33. The apertures 20 and 30 in the rings 2 and 3, respectively,

afford communication between the tubular passages thus formed in the top and bottom of the radiator and the columns 12. The ends of the spacers 2 and 3 are of sufficient thickness or, by the addition of flanges, as 31, are given sufficient width, to provide ample bearing surface on the adjacent surfaces of the halves 1 and 10.

One of the halves, as 10, may be provided 10 with a male flange 17 which projects within the aperture 15 of the adjoining unit, that is, the aperture in the half 1 of this adjoining unit. Preferably the flange projects sufficiently that it engages the inner periphery of the spacer ring 3 within this adjoining unit, thus serving to maintain this ring in position. In this way the several spacer rings may be held in position, not only by the frictional grip of the two halves, but in 20 addition by the positive action of the flanges 17.

At the ends of the radiator means are provided for closing the ends of the transverse channels 22 and 33 at top and bottom, 25 respectively, formed by the aligned spacers 2 and 3. At the top chamber caps 4 and 40 may be provided, the cap 4 having a male flange 41 fitting within the terminal spacer 2 to position it, and being interiorly threaded as indicated at 43, for the reception of a clamping rod 42 which extends through the channel 22. The other end of the channel 22 is closed by a cap 40, likewise threaded as indicated at 44, for the reception of the 35 end of the clamping rod 42, this cap 40 fitting over the flange 14 of the terminal unit. A filling opening 45 may be provided in this cap 40, normally closed by a screwed-on cover 47, and a safety valve indicated at 46 may be received in the cover 47 communicating with the filling opening 45 to control the pressure within the radiator. It will be noted that the top of the cover 47 is dished 40 slightly, whereby it will catch and retain water of condensation dripping from the relief valve 46, this water subsequently evaporating.

At the bottom of the radiator we provide caps 5 and 50 corresponding to the caps 4 and 40 and connected by a series of clamping rods 52 extending between the caps 5 and 50, but preferably spaced outward of the axis of the channel 33. As shown, the rods 52 are received within bosses 53 of the cap 5, their other ends extending through the cap 50 and receiving clamping nuts 54 exteriorly thereof. With these caps 5 and 50 may be associated the means for supporting the radiator and permitting its movement from place to place. To this end we have shown sockets 58, provided for the reception of the shanks 80 of casters 8, the rings carrying the sockets 58 being formed integrally with the respective caps 5 and 50.

65 Preferably the cap 5 is formed of two

parts, the main portion being formed as a ring upon which is secured a light cover 51 to close the end of the ring. We prefer also that means such as the casing 60, be provided and attached to the ring 5 for the support of a switch 61. The lead wires 62 extend to an aperture 55 affording communication between the switch casing 60 and the interior of the ring 5.

It will be noted that the clamping rods 52 75 are angularly spaced and, in effect, form a cage within which is received a tube 62 for the reception of a heating element, generally indicated by the numeral 6, and to which the lead wires 62 are connected. The tube 80 62 is closed at the end corresponding to the cap 50, but is flanged as is indicated at 62 at its other end, and this end is left open. To retain the tube in place and to prevent leakage past its open end, a collar 56 is 85 threaded within the ring 5 to clamp the flange 63 between itself and a shoulder 57 of the ring.

If it is deemed necessary to indicate the depth of water in the radiator, a water 90 glass 7 may be employed, the fittings 70 and 71 being threaded through the column 12 of a terminal unit into a plate 72 soldered or otherwise secured to the inside of this column. Such a plate may be secured to the 95 half unit 10 prior to the assembly of this unit with a half section 1 to form the complete unit.

What we claim as our invention is:

1. A multi-unit pressed metal radiator 100 construction, each unit comprising complementary halves permanently joined about their margins, and having aligned apertures inward thereof, a spacer ring interposed between the two halves of a unit, surrounding the apertures, one half only of each unit having a flange surrounding the aperture and projectable to be received within the aperture of the adjoining unit to align the units and to directly engage and align the 105 spacer therein with the spacer within the first unit, and means for clamping the several units together in the line of the apertures.

2. In a radiator, in combination with a 115 plurality of units having aligned apertures, a cap closing the outermost aperture at one end of the radiator, a ring closing the aperture at its other end, a plurality of clamping rods extending between said cap and said ring, and arranged about the axis of the aligned apertures, a tube open at one end, and having its open end received within the collar and its closed end supported by said rods, and means for securing the open end of 120 the tube in non-leaking relation to the ring.

3. In a radiator, in combination with a plurality of units having aligned apertures, a cap closing the outermost aperture at one end of the radiator, a ring closing the ap- 130

erture at its other end, a plurality of clamping rods extending between said cap and said ring, and arranged about the axis of the aligned apertures, a tube open at one end, 5 and having its open end received within the ring and its closed end supported by said rods, a flange surrounding the open end of said tube, the ring being shouldered to

receive said flange, and a clamping ring threaded in said ring and clamping said 10 flange between itself and said shoulder.

Signed at Seattle, King County, Washington, this 6th day of November, 1925.

CLARENCE H. PICKERING.
JOHN CAMPBELL.
